UNITED STATES PATENT OFFICE.

LOUIS COHEN AND JOSEPH O. MAUBORGNE, OF WASHINGTON, DISTRICT OF COLUMBIA.

ELECTRICAL SIGNALING.

Application filed October 25, 1920. Serial No. 419,383.

To all whom it may concern:

Be it known that we, LOUIS COHEN and JOSEPH O. MAUBORGNE, residing in Washington, District of Columbia, have invented 5 certain new and useful Improvements in Electrical Signaling, of which the following is a specification.

This invention relates to the art of radio signaling, and particularly receiving radio 10 signals and system for use in practising same.

The object of the present invention is to 15 eliminate electro-static disturbances and other interference in the reception of radio signals and thus improve the clearness and reliability of radio communication.

In a pending application, Serial Number 401,752, we have described a method for 20 receiving radio signals in which resonance wave coils are introduced in an antenna circuit, and utilizing the wave development 25 effects produced by electrical excitation acting on the antenna. The present invention is another modification of the same general 30 idea embodying novel features with a view to securing still greater improvements in the results desired, namely, more effective elimination of static disturbances and other interference in the reception of radio signals.

The method involves the use of an open 35 antenna circuit, no ground, and the use of resonance wave coils as part of the antenna circuit, thereby effecting a wave development 40 in the antenna system and suitably connecting an indicator either direct or to a secondary coupled circuit to a loop of potential point on the wave coil. The resonance wave coil which we shall designate hereinafter simply as "wave coil", is preferably 45 in the form of a long helix, uniformly wound with wire, single or multiple layer winding, the electrical constants of which, inductance, capacity, and resistance, are of a distributed character and a wave development effected on the wave coil by an electrical excitation of the antenna. The wave 50 coil is wound with a large number of turns per unit length, and also enclosed for part of its length, or the entire length, by one or more adjustable grounded metal tubes suitably placed on the wave coil, the object being to secure a large inductance and a large 55 capacity per unit length so as to get in a comparatively short length the equivalent condition of a long line in the matter of

wave development. Also by the adjustment of the position of the metal tubes tuning is effected which produces an increase in the intensity of the signal to be received and a redirection of foreign disturbances such as 60 electrostatic effects. One or all of the metal tubes surrounding the wave coil may be directly connected to ground or through a loop circuit consisting of an inductance and capacity in parallel, the constants of which are 65 suitably adjusted in relation to the frequency of the signals it is desired to receive.

The principle involved is to permit all 70 electrical effects acting on the antenna to pass through the wave coils before reaching the receiving instrument. It is well-known that an electrical shock effect such as may 75 be produced by electrostatic disturbances, strays, or nearby radio stations, has a much steeper wave front than the oscillations produced by incoming signals which are regular in character in the matter of intensity and frequency. The electrical shock effects of steep wave fronts are more rapidly attenuated in passing through a conductor in 80 which a wave development is effected by these electrical disturbances, and as a result a much higher ratio of signal to static is obtained in the receiving instrument. By suit-

ably adjusting the constants of the wave coil 85 in the matter of length, number of turns, etc., and also properly adjusting the position of the metal tubes surrounding the coils, all 90 in relation to the wave length of the signals to be received, a condition is obtained where electro-static or other foreign disturbances are largely attenuated, leaving the receiving instrument free from these disturbances and acted on only by the signals it is desired 95 to receive. Further the use of the loop circuit in the ground connection of the metal tubes is of considerable importance in bringing about the results desired. If the loop circuit is tuned to the frequency of the signal it is desired to receive, it offers an extremely 100 high impedance to the signal received, preventing any of the signal energy from leaking away by that path to the ground, but offering a ready path for any other electric disturbances which are not exactly of the 105 same frequency. It is evident also that the loop circuit with its ground connection, functions in a different way when the system is acted upon by foreign disturbances than it does when acted upon by the signals of the 110

particular frequency it is desired to receive. The natural period of the system is different in the two cases. That is, the free oscillations produced by any shock excitation 5 which may be due to electro-static disturbances or other electrical disturbances of the same character are of a different frequency than that of the signal which it is desired to receive and to which the antenna system 10 is adjusted, and therefore the tuned receiving circuit which is coupled to the wave coil and tuned to the frequency of the signals responds but faintly to the free oscillations 15 of foreign disturbances which are of a different frequency.

In other words, in the arrangement disclosed in this invention any electrical effect acting on the antenna is propagated along the wave coil in the form of an attenuated 20 wave, the attenuation and wave length depending upon the character of the electrical disturbances acting on the antenna in relation to the circuit arrangement. By properly adjusting the length of wire on the 25 wave coil, the position and dimension of the metal tubes, and constants of the loop circuit all in relation to the frequency of the signal to be received, a condition may be realized where the attenuation of the signal current 30 is very feeble, while other interfering effects of different frequencies are attenuated very sharply in their propagation along the wave coil.

It should also be borne in mind that for 35 the propagation of electrical waves in the free ether, there is one definite fixed relation between the frequency and the wave length, but in the case of propagation of electrical waves along coils, the relation between frequency and wave length is dependent upon 40 the electrical characteristics of the coil, its inductance and its capacity, which also offers a means for controlling the wave length. The adjustment of the metal tube and the 45 grounded loop circuit have an equivalent effect as changing the electrical characteristics of the coil, and hence, cause a change in the wave length of any electrical effect propagated along the wave coil. The arrangement involving this invention offers, 50 therefore, a means of controlling both the wave length and the attenuation constants of the wave propagated along the wave coil, and by suitable adjustments, these properties 55 can be advantageously employed to accentuate the signal to be received and practically nullify all foreign disturbances in their effects upon the detecting instrument. By placing several metal tubes on the wave 60 coil, each grounded through different loop circuits, there is obtained the equivalent effect of several separate wave coils of different electrical constants joined together electrically due to the direct connections and 65 electro-magnetic relation between the dif-

ferent parts of the wave coil, and in this instance, any single frequency current may produce a multiplicity of waves of different wave lengths, and with proper adjustments of the phase relations of the different waves 70 produced by the signal to be received, an additive effect upon the detector is obtained. Obviously, this offers an additional means of differentiating the signal effect from any foreign disturbances. 75

The circuit combination described above offers a very effective method for increasing greatly the ratio of signal to static, thereby improving the clearness and accuracy in 80 radio communication.

The principle of operation and the method of using our invention can be better understood by reference to the accompanying diagrammatic figures which show typical embodiments of the invention and form part of 85 this specification.

In the accompanying drawings:

Figure 1, is a diagrammatic view of a system for carrying out the invention in which the receiving circuit is coupled electro-statically to a wave coil. 90

In Figure 2, the receiving circuit, including the detector, is connected directly to a suitable point on a wave coil.

Another embodiment of our invention is 95 shown in Figure 3 in which an additional wave coil is connected electro-statically to a suitable point on a wave coil of the antenna system, and the receiving circuit proper, including the detector is coupled 100 electro-magnetically to the additional wave coil.

The arrangement shown in Figure 4 differs from that of Figure 3 in that the electro-static connection of the wave coil of the 105 antenna system passes through a small variable condenser before being connected to an additional wave coil, and one point of said condenser is grounded through a suitably adjusted loop circuit. 110

In Figure 5, an arrangement is shown in which the receiving circuit, including the detector, is coupled electro-magnetically to a wave coil of the antenna system.

Figure 6 is an embodiment of our invention in which the end part of the wave coil of the antenna system is closed upon itself through a suitable inductance and capacity, and the receiving circuit, including the detector, is coupled electro-magnetically to 115 the wave coil of the antenna system, and also to the inductance of the connecting circuit, and 120

Figure 7 is a diagrammatic view of a possible modification of our invention. 125

Having particular reference to the drawings, and in connection with which, like characters of reference will designate corresponding parts thereof, in Figure 1, the antenna 1 is connected to a variable inductance 130

2, in series with variable capacity 3, and in series with two wave coils 4 and 5, constituting the antenna circuit. 6 and 6' indicate metal tubes surrounding the wave coil 4. 5 The metal tubes 6 and 6' which are electrically connected by a lead 7, are movable and can slide along the coil 4. Also the metal tubes 6 and 6' are connected to a loop circuit consisting of a variable inductance 8 and a 10 variable capacity 9, connected in parallel and then to ground 10. 11 indicates a metal ring movable along coil 5, the metal ring being connected electrically to one point of a circuit consisting of a variable inductance 15 12 and a variable capacity 13. 14 represents an indicating instrument connected across the condenser terminals 13.

The operation is as follows:

In Figure 1, the tuning of the antenna system is accomplished by varying inductance 2, capacity 3, and the adjustment of the metal tubes 6 and 6' along the coil 4. Experience has shown that by suitably adjusting the position of the metal tubes 6 and 25 6' relative to each other and varying their positions on the coil very sharp tuning is obtained. Further by adjustment of the metal tubes 6 and 6' it is possible either to bring in the signal and eliminate foreign 30 disturbances or vice versa. Hence the adjustment of the metal tubes plays a very important part in changing the ratio of static to signal acting on the receiving instrument. In fact, it may be said that this arrangement 35 offers for the first time a means for varying the ratio of static to signal. The tuning of the loop circuit 8-9 is also very effective in increasing the loudness of the signal it is desired to receive without at the same time 40 bringing in static disturbances. In fact, with proper adjustment of the loop circuit 8-9, the signals are intensified, while the electrostatic or other foreign disturbances are reduced. The ring 11 is adjustable 45 along coil 5, and in actual operation it is moved along the coil until the loudest signal is obtained. The ring constitutes an electrostatic coupling between the coil 5, and the receiving circuit 12-13. Evidently the ring 50 11 must be adjusted so as to be on a loop of potential point of coil 5. Circuit 12-13 is tuned to the frequency of the incoming signal. 14 indicates a suitable detector which may be any one of the well-known types, 55 such as the three electrode tube, or any other detector connected across the terminals of the secondary condenser 13.

Figure 2 differs only from Figure 1 in the method of connecting the receiving circuit 60 12-13 to the wave coil 5. In this arrangement a direct connection is used. The circuit 12-13 connects to variable point 17 along the coil 5, said connection being moved along the coil 5 until the point of 65 maximum sensitiveness is obtained, which,

in this case, would be the loop of potential point on the coil 5.

Another embodiment of the invention is shown in Figure 3 in which an additional wave coil 15 is used. The wave coil 15 is 70 connected electrostatically through metal ring 11 to the wave coil 5, and the secondary circuit 12-13 is coupled electro-magnetically to the wave coil 15. The object of using additional wave coil 15 is to produce 75 an increase in the selectivity of the system, thereby still further reducing any foreign disturbances which might otherwise find their way into the receiving system.

Figure 4 differs from Figure 3 by the introduction of an additional variable condenser 18 into the connecting lead which connects coil 15 to the metal ring 11 which is in its turn electrostatically coupled to coil 5. 80 In addition, loop circuit 19-20, grounded 85 to 10, is also connected to one point of condenser 18. The purpose of this loop circuit 19-20 is to further drain off all residual foreign disturbances which might have found their way into coil 15; in other words, 90 the use of coil 15, loop circuit 19-20, and condenser 18 is simply an additional means of improving the selectivity of the system and further reducing foreign disturbances from acting on the receiving circuit proper 95 12-13 associated with its detector 14.

In Figure 5, is shown an embodiment of the invention in which the electro-static coupling represented by the metal ring 11, referred to in the previous diagrams, is here 100 replaced by an electromagnetic coupling 16. Also it may be noted that in this arrangement, a variable condenser 27 is shown in the lead which connects the metal tubes 6 and 6' to the loop circuit 8-9. This is 105 sometimes helpful in making the loop circuit more effective in its action and in the reduction of static disturbances.

The embodiment shown in Figure 6 differs somewhat from the previous figure in 110 the terminal arrangement used, but embodying the same general principles. In this arrangement coil 5 is divided into two parts, the end part of which is closed upon itself through a tuned circuit, consisting of inductance 22 and capacity 23. The receiving circuit 12-13 is coupled to the wave coil 5 and also to the tuned circuit 22-23.

It is obvious that various modifications of the circuit arrangements may be made 120 without departing from the spirit of the invention. For the purpose of illustration two metal tubes connected electrically are shown throughout in all the figures, but equally good results are obtained by using 125 either a single tube or several tubes, and the tubes 6, 6', 6'', and 6''' may or may not all be connected electrically. Further, as shown in Figure 7, we may connect either all of the tubes to ground through a single 130

loop circuit or independent loop circuits, including inductances 8 and 8' and variable capacities 9 and 9', or only a portion of the tubes may be connected to ground, and the 5 rest remain free. Either of these variations if proper adjustments are made, will give the results desired. Also in the case of wave coils employed only two wave coils are shown in the drawing, but under certain 10 conditions it may be preferable to use only one or a larger number of wave coils. It is clearly within the province of the invention to introduce these variations.

We claim:

15 1. A system for radio signaling in which the received signals or other electrical effects acting on an ungrounded antenna system are caused to pass through a wave coil and produce a wave development on said 20 wave coil, said wave coil being operatively associated with adjustable metal tubes and a suitable indicating instrument.

2. A system for radio signaling in which the received signals or other electrical effects 25 acting on an ungrounded antenna system are caused to pass through wave coils, and produce wave developments on said wave coils, and said wave coils being operatively associated with adjustable grounded metal tubes 30 and a suitable indicating instrument.

3. A system for radio signaling in which the received signals or other electrical effects acting on an ungrounded antenna system are caused to pass through 35 wave coils before reaching the receiving instrument, one of said wave coils being enclosed in two adjustable grounded metal tubes separated from each other, said metal tubes being connected to ground through a 40 tuned loop circuit and suitable indicating instrument being operatively associated with another of said wave coils.

4. A system for radio signaling in which the received signals or other electrical effects 45 acting on an ungrounded antenna system are caused to pass through wave coils before reaching the receiving instrument, one of said wave coils being enclosed in several adjustable grounded metal tubes separated from each other, said metal tubes being connected to ground through a tuned loop circuit, and suitable indicating instrument being operatively associated with another of the said wave coils.

5. A system for radio signaling in which the received signals or other electrical effects 50 acting on an ungrounded antenna system are caused to pass through wave coils before reaching the receiving instrument, one of said wave coils being enclosed in adjustable metal tubes, certain of said metal tubes being separately connected to ground through a tuned loop circuit, and a suitable indicating instrument being operatively associated with one of said wave coils.

6. A system for radio signaling in which the received signals or other electrical effects acting on an ungrounded antenna system are caused to pass through wave coils before reaching the receiving instrument, one of 70 said wave coils being enclosed in adjustable metal tubes, only one of said metal tubes being connected to ground through a tuned loop circuit, and a suitable indicating instrument being operatively associated with one 75 of said wave coils.

7. A system for radio signaling in which the received signals or other electrical effects acting on an ungrounded antenna system are caused to pass through a wave coil 80 before reaching the receiving instrument, said wave coil being enclosed in two adjustable grounded metal tubes electrically connected, said metal tubes being connected to ground through a tuned loop circuit and 85 suitable indicating instrument being operatively associated with the said wave coil.

8. A system for radio signaling in which the received signals or other electrical effects 90 acting on an ungrounded antenna system are caused to pass through two wave coils connected electrically but separated from each other, one of said wave coils being enclosed in two adjustable metal tubes which are grounded through a tuned loop circuit 95 and the other of said wave coils being operatively associated with receiving means.

9. A system for radio signaling in which the received signals or other electrical effects 100 acting on an ungrounded antenna system are caused to pass through two wave coils connected electrically but separated from each other, one of said wave coils being enclosed in adjustable grounded metal tubes, the other of said wave coils being electrostatically 105 associated with a third wave coil, and receiving instruments being electrically associated with the said third wave coil.

10. A system for radio signaling in which the received signals or other electrical effects 110 acting on an ungrounded antenna system are caused to pass through two wave coils connected electrically, one of said wave coils being enclosed in adjustable metal tubes, said metal tubes being connected to ground through tuned loop circuits; the other of said wave coils being electrostatically associated with a third wave coil through a variable condenser, the connecting point of the condenser and said third wave coil being 115 grounded through a tuned loop circuit, and also the said third wave coil being operatively associated with receiving means.

11. A system for radio signaling comprising an antenna, tuning elements, two 125 wave coils, one of said wave coils being enclosed in adjustable metal tubes, said metal tubes being connected to ground through a tuned loop circuit, the other of said wave coils being adjustably connected electrically 130

to a tuned circuit and a detecting instrument associated with said tuned circuit.

12. A system for radio signaling comprising an antenna, tuning elements, two wave coils, one of said wave coils being enclosed in adjustable metal tubes, said metal tubes being connected to ground through a tuned loop circuit, another tuned circuit being connected to an adjustable point on the other 10 of said wave coils, and a suitable indicating instrument being associated with said tuned circuit.

13. A system for radio signaling comprising an antenna system, which consists of an antenna, tuning elements, two wave coils, all connected in series, one of said wave coils being enclosed in adjustable metal tubes, said metal tubes being electrically connected and also connected to the ground 20 through a tuned loop circuit; the other of said wave coils being electro-statically connected by means of a sliding metal ring on it to a third wave coil, a tuned circuit being

electro-magnetically associated with the said third wave coil and a detecting instrument 25 associated with said tuned circuit.

14. A system for radio signaling comprising an antenna system which consists of an antenna, tuning elements, two wave coils, one of said wave coils being enclosed in adjustable metal tubes, said metal tubes being electrically connected and grounded through tuned loop circuits; the other of said wave coils being associated electrically with a third wave coil by means of a metal ring 35 sliding over the second said wave coil, said metal ring being connected through a variable condenser to the third of said wave coils, and said variable condenser being grounded through a tuned loop circuit, another tuned circuit being associated electro-magnetically with the third of said wave coils and an indicating instrument connected to said tuned circuit. 40
